UNITED STATES PATENT OFFICE.

RAY P. FARRELL, OF OXNARD, CALIFORNIA.

SWITCH-BOX.

1,133,946.

Specification of Letters Patent.

Patented Mar. 30, 1915.

Application filed February 17, 1912. Serial No. 678,193.

To all whom it may concern:

Be it known that I, RAY P. FARRELL, a citizen of the United States, residing at Oxnard, in the county of Ventura and State 5 of California, have invented new and useful Improvements in Switch-Boxes, of which the following is a specification.

The present invention relates to improvements in switch boxes for electric wiring.

10 In carrying out my invention it is my primary object to provide a switch box having means whereby the box may be attached to a studding, the said box being further provided with means whereby laths may be 15 easily and quickly connected therewith, thus obviating the necessity of the employment of a board or the like which is provided with an opening for the reception of the switch box.

20 It is a further object of the invention to construct a switch box having a normally open side, the edges of the said side being of such a formation as to receive and retain thereon additional boxes or sections of 25 boxes, so that the main or supporting box may carry a plurality of auxiliary boxes, thus changing the device into a gang box.

With the above objects in view and others 30 of a similar nature as will hereinafter be set forth, the invention resides in the novel construction, arrangement and combination of elements set forth in and falling within the scope of the appended claims.

In the drawings, Figure 1 is a perspective 35 view of a switch box constructed in accordance with the present invention, the side plate being removed. Fig. 2 is a similar view showing the side plate in position. Fig. 3 is a vertical longitudinal sectional view of the device illustrated in Fig. 2. Fig. 4 is a perspective view of the removable side plate.

40 As is well known in the art, switch boxes for electric conduits are sustained in place 45 between the studs of partitions through the medium of a board which is secured between two of the said studs. This board is sawed or otherwise provided with an opening for the reception of a box, the ordinary box being formed with perforated ears through 50 which are passed screws for retaining the box upon the board. It will be readily understood that by such a construction a great amount of time and labor is expended, 55 and it is the primary object of the present

invention to construct a box which is provided with an open side wherein either a side plate or a box section may be readily inserted, the said box having angularly arranged flanges provided with openings 60 adapted to receive nails or the like to permit of the box being securely attached to a stud, while the said removable side plate is provided with pockets for the reception of laths, thus dispensing with the board com- 65 monly employed for sustaining the box.

Referring now to the drawings in detail, the numeral 1 designates my improved box. This box 1 embodies a top, 2, a bottom 3 a rear or back 4 and a side 5, as well as a removable plate for the open side, as will hereinafter be more fully set forth. The closed side 5 is formed with ears 6 and 7, the same extending above the top 2 and below the bottom 3. The side 5 is further provided 70 with a flange 8, the same being preferably integrally formed with the box and being arranged at a right angle to the ears 6 and 7. The ears, as well as the flange are provided with openings 9, the said openings being adapted to receive securing elements, such as nails whereby the box may be retained upon a stud 10. The side 5 beyond 75 its connections with the stud is formed with suitable openings 12 for the reception of the 80 electric wiring, while the back 4 as well as the bottom 3 are provided with similar openings designated by the numerals 13 and 14, respectively. The back 4 is formed with projections 14', the same being adapted to 85 serve as stop members for the removable side or for the sections which are employed 90 for making a gang box as will hereinafter be 95 more fully described.

The longitudinal edges of the top 2 and bottom 3 are curved to provide substantially semi-cylindrical ways, designated respectively by the numerals 15 and 16. The material from which the box is constructed is preferably of a resilient metal and the said 100 ways 15 and 16 are centrally slotted to provide the inturned spring tongues 17 and 18.

The numeral 19 designates the side plate for the box, this plate is constructed of a single piece of resilient material comprising 105 a substantially rectangular member of a size equalizing the space provided between the top and bottom and the rear wall of the box. The plate 19 is provided with a plurality of longitudinally extending slits 20, 110

the material between the said slits being bent outwardly to form lugs 21, the plate is centrally provided with longitudinally extending slits, and the metal between the said slits is bent to provide a stop 22. The stop 22 is arranged centrally of the plate and immediately between the lugs 21, so that the said stop will provide a support for the upper lath 23 as well as to provide a means 10 for preventing upward movement of the lower lath 24. The upper and lower longitudinal edges of the plate 19 are formed with offset members 25 and 26, the same completing the pockets for the laths 23 15 and 24. The plate 19 has its longitudinal edges inclined from the offset members 25 and 26, and the said plate is further provided with cut away or depressed portions 29 and 30, the latter adapted to be engaged 20 by the spring tongues 17 and 18 while the inclined edges provide means whereby the said plate may be readily slid within the ways 15 and 16.

What is claimed is:

In combination with a metallic switch 25 box having an open end and open side, a plate removably mounted upon the box so as to close the open side of said box, an outwardly projecting upper and lower stamping 30 being step shaped in contour and mounted upon said plate, an outwardly extending right angular stamping formed midway between said step-shaped members, and an upper and lower pair of outwardly extending right angular stamped lugs, each pair 35 of said lugs disposed midway between one of said first mentioned step like stampings and said last named right angular stamping and being spaced apart on either side of the latter whereby to receive a lath. 40

In testimony whereof I affix my signature in presence of two witnesses.

RAY P. FARRELL.
